[57] CLAIM

The ornamental design for a chair, as shown and described.

DESCRIPTION

FIG. 1 is a front perspective view of a chair showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front perspective view of a second embodiment of the chair shown in FIG. 1;

FIG. 9 is a front perspective view of a third embodiment of the chair shown in FIG. 1; and

FIG. 10 is a front perspective view of a fourth embodiment of the chair shown in FIG. 1.

The base indicated by means of broken lines in FIG. 1 has been shown for illustrative purposes only.
